(57) **CLAIM**

The ornamental design for a carriageable multimedia receiver, as shown and described.

DESCRIPTION

FIG. 1 is a perspective view of carriageable multimedia receiver showing my design.

FIG. 2 is a front elevational view thereof;
FIG. 3 is rear elevational view thereof.

FIG. 4 is left elevational view thereof;
FIG. 5 is a right elevational view thereof;
FIG. 6 is a top view thereof; and,
FIG. 7 is a bottom view thereof.

1 Claim, 4 Drawing Sheets

FIG. 1

FIG. 2

FIG. 3

FIG. 4

FIG. 5

FIG. 6

FIG. 7
